MOVING MECHANISM FOR PINS,
BROOCHES, ETC.

Joseph Fernandez, Newark, N. J.

Application October 25, 1939, Serial No. 301,140

6 Claims. (Cl. 63—31)

This invention relates to new and useful improvements in a moving mechanism for pins, brooches, etc.

More specifically, the invention proposes the construction of a pin or brooch consisting of an ornament body having an opening into which a spring motor is adapted to be mounted to operate movable members.

Still further it is proposed to provide a supports for a picture connected with said spring motor in a manner to be moved thereby when the spring motor functions.

Still further it is proposed to provide an ornament body with a cam for controlling the path of movement of the support, and to provide the support with a picture adapted to cooperate with a complementary picture stationarily mounted on the body in a manner to give the appearance of a changing scene located within the brooch.

Still further it is proposed to provide a crystal mounted on said ornamental body in a manner to extend over and cover the pictures.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a partial elevational view of a person wearing a pin or brooch constructed according to this invention.

Fig. 2 is an enlarged elevational view of the pin or brooch with the crystal removed.

Fig. 3 is a sectional view taken on the line 3—3 of Fig. 2.

Fig. 4 is a view looking in the direction of the line 4—4 of Fig. 3.

Fig. 5 is a developed view of the cam per se.

Fig. 6 is an enlarged perspective view of the clip mounted upon the support.

Fig. 7 is a view similar to Fig. 2 illustrating a modification of the invention with the crystal removed.

The moving mechanism for pins or brooches, according to this invention, includes an ornament body 10 having an opening 10^a. The ornament body 10 is substantially circular in form and is provided with a plurality of ornamental members 10^b mounted upon the front face thereof. These ornaments 10^b, as shown, are in the form of flowers mounted on the face thereof or may be of any other desired construction. A conventional pin 11 is mounted across the back face of

the ornament body 10 for permitting the same to be engaged upon a person's dress 12 as shown in Fig. 1. This pin 11 has one end pivotally mounted and the other end pointed and engageable with a complementary keeper 11^a for holding the same in a closed and operative position.

A spring motor 13 is mounted within the opening 10^a of the ornament body 10. This spring motor 13 is of conventional construction and is provided with an escapement not shown on the drawing for preventing the same from unwinding too rapidly. It has a stem 13^a extended from the top thereof and projecting beyond the periphery of the ornament body 10 for the purpose of permitting the spring of the motor 13 to be conveniently wound.

A support 14 for a picture or the like is connected with the spring motor to be moved thereby. This support 14 is constructed of resilient spring metal and is substantially of U-shape and has one of its ends 14^a connected to the rotative spindle of the spring motor 13.

A cam 15 is positioned between the adjacent edges of the spring motor 13 and the ornament body 10. It is provided with a cam groove 15^a into which the free end of the support 14 is extended in a manner to control the path through which the support will move when rotated with the spring motor. The support 14 is further provided with a spring clip 16 for receiving and releasably holding a picture 17. In the form of the invention shown the picture 17 takes the form of a moon which is adapted to move about the ornament body when the support 14 is rotated by the spring motor.

A complementary picture 18 in the form of a country scene is releasably mounted within the ornament body 10 to the front of the support 14. This picture 18 has its edges releasably engaged into spring clips 19 mounted on the free peripheral edge of the cam 15. A crystal 20 is engaged over the outer edge of the cam 15 and is releasably held therein in a manner to be removed for permitting the pictures 17 and 18 to be interchanged with other desired pictures.

The operation of this form of the invention is as follows:

The brooch is positioned upon one's dress in a conventional manner and the spring motor 13 is wound through the medium of the rotatable stem 50 13^a. When the spring motor becomes wound it will cause the support 14 to rotate and the tail thereof which is engaged into the cam groove 15^a will cause the picture 17 mounted thereon to move forwards and backwards with respect 55

to the spring motor 13. As the spring rotates the support 14, the picture 17, which is in the form of a moon, will be correspondingly rotated to cause the moon to rise at one side of the picture 18 and go down at the other side of the picture. The cam groove 15^a is so positioned with relation to the picture 18 that it will cause the moon 17 to move slightly forwards when in the exposed position and move backwards so as not to strike the picture 18 when moved into the retracted position.

In the form of the invention shown in Fig. 7 the construction of the moving mechanism for pins and brooches is similar to that previously described except for the shape of the ornament body 10'. In this form of the invention the ornament body 10' is hexagonal in shape and carries the cam 15. In other respects this form of the invention is similar to the previous form and similar parts may be identified by corresponding reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A moving mechanism for pins, brooches and the like, comprising an ornament body having an opening, a spring motor mounted in said opening, a support for a picture or the like connected with said spring motor to be moved thereby, a cam for controlling the path of movement of said support, a picture mounted on said support, a complementary picture stationarily mounted on said body, and a crystal covering said pictures.

2. A moving mechanism for pins, brooches and the like, comprising an ornament body having an opening, a spring motor mounted in said opening, a support for a picture or the like connected with said spring motor to be moved thereby, a cam for controlling the path of movement of said support, a picture mounted on said support, a complementary picture stationarily mounted on said body, and a crystal covering said pictures, said spring motor being provided with a rotative stem extending beyond the periphery of said ornament body for permitting the spring motor to be conveniently wound.

3. A moving mechanism for pins, brooches and

the like, comprising an ornament body having an opening, a spring motor mounted in said opening, a support for a picture or the like connected with said spring motor to be moved thereby, a cam for controlling the path of movement of said support, a picture mounted on said support, a complementary picture stationarily mounted on said body, and a crystal covering said pictures, said support being constructed of resilient spring material and having one end attached to the rotative spindle of said spring motor and the other of its ends extended into a cam groove formed in said cam.

4. A moving mechanism for pins, brooches and the like, comprising an ornament body having an opening, a spring motor mounted in said opening, a support for a picture or the like connected with said spring motor to be moved thereby, a cam for controlling the path of movement of said support, a picture mounted on said support, a complementary picture stationarily mounted on said body, and a crystal covering said pictures, said support being provided with a spring clip for fixedly but releasably holding said picture in position thereon to permit the picture to be inter-changed with other pictures.

5. A moving mechanism for pins, brooches and the like, comprising an ornament body having an opening, a spring motor mounted in said opening, a support for a picture or the like connected with said spring motor to be moved thereby, a cam for controlling the path of movement of said support, a picture mounted on said support, a complementary picture stationarily mounted on said body, and a crystal covering said pictures, said complementary picture having its bottom edge releasably engaged into spring clips mounted on the free edge of said cam so as to be inter-changed with other complementary pictures.

6. A moving mechanism for pins, brooches and the like, comprising an ornament body having an opening, a spring motor mounted in said opening, a support for a picture or the like connected with said spring motor to be moved thereby, a cam for controlling the path of movement of said support, a picture mounted on said support, a complementary picture stationarily mounted on said body, and a crystal covering said pictures, said crystal covering being removably mounted so that it may be removed when it is desired to inter-change said picture and complementary picture with other pictures.

JOSEPH FERNANDEZ.
